CLAIM

The ornamental design for a building for the selling of ice cream, substantially as shown and described.

DESCRIPTION

FIG. 1 is a front view of a building for selling ice cream showing my new design;

FIG. 2 is a right side view thereof;

FIG. 3 is a rear view thereof; and

FIG. 4 is a top view thereof.

The left side view would be a mirror image of FIG. 2. The bottom is plain.

FIG. 1

FIG. 2

FIG. 3

FIG. 4
